UNITED STATES PATENT OFFICE.

ISAAC PEACOCK, OF SHORTSVILLE, NEW YORK.

IMPROVEMENT IN HORSESHOES.

Specification forming part of Letters Patent No. 38,451, dated May 5, 1863.

To all whom it may concern:

Be it known that I, ISAAC PEACOCK, of Shortsville, in the county of Ontario and State of New York, have invented a new and Improved Horseshoe; and I do hereby declare that the following is a full, clear, and exact description thereof, reference being had to the accompanying drawings, making a part of this specification, in which—

Figure 1 shows the improved shoe inverted and nailed to the foot of a horse. Fig. 2 is a bottom view of the improved shoe. Fig. 3 is a transverse section through the shoe, taken at the point indicated by the red line $x x$ in Fig. 2.

Similar letters of reference indicate corresponding parts in the three figures.

This invention relates to the improved shoe the form of which I manufacture with the machine for which Letters Patent were granted to me bearing date the 20th day of January, 1863.

The nature of my invention consists in making a very strong and durable horseshoe, which possesses comparatively little weight and which will give a firm and substantial support and bearing to the hoof and a better support to the horse than the triple-calked shoes, by constructing the shoe with a continuous calk or rim extending unbroken from heel to heel, and making this calk at or nearly at right angles to the sole-plate, and also combining with this arrangement an inner ridge for strengthening and stiffening the inner edge of the sole-plate and giving a firm support to the hoof at this point, all as will be hereinafter described.

To enable others skilled in the art to make and use my invention, I will proceed to describe its construction and operation.

This invention is intended more especially for cavalry-horses, to make them sure-footed, to give their feet a better anchorage or hold, and to protect their hoofs from injury in many ways, but more particularly by preventing the heads of the shoe-nails from striking stones or other solid substances and irritating the quick or sensitive part of the hoof; also, to support the hoof more firmly, both at its outer edge and near the frog, so that the horse will not

be liable to sprains or bruises of the feet. To this end I construct a shoe by means of machinery and otherwise, as described in my patent aforesaid, the sole of which consists of a thin plate, the upper surface of which is flat, as shown at a , Fig. 2, terminating around its inner edge in a curved depression, b . This surface conforms to the curvature and flat surface of the sole of the hoof surrounding the "frog," and gives a firm tread and a good support to the heel, sides, and toe of the foot. The "calk" or outer ridge, d , projects down some distance below the lower flat surface, a' , of the sole-plate and inclines outward, forming a continuation of the outer surface of the horny case. The bottom edge of this ridge d is in a plane parallel with the surface of the sole-plate, and this ridge extends from heel to heel around the shoe in an unbroken line, terminating only at the heel of the shoe in the contracted curves. (Shown in Figs. 1 and 2 of the drawings.) The ridge d may be made flat on its bottom surface, or this edge may be sharpened for preventing the horse from slipping in frosty weather; but whether it be sharpened or not, it will be seen that the contracted curves at the heel of the shoe will give the shoe a sufficient hold or anchorage to prevent the horse from slipping under all ordinary circumstances. The inner edge, e , of the shoe is strengthened by forming on its lower surface a ridge, e , which is produced in the manufacture of the shoe by upsetting the metal in forming the depression b and the flat bottom surface of the sole-plate. This ridge e projects only so far below the surface of the sole-plate as it is found necessary to stiffen the inner edge of this plate, and between this ridge e and the calk d the perforations are made to receive the shoe-nails $g g g$. (Shown in Fig. 1.) It is not necessary to groove the bottom of the sole-plate farther than I have above described, as the ridge e and the calk d will protect the nail-heads from contact with stones and other hard substances.

Now, it will be seen from the above description that the shoe is made very light and strengthened by the ribs d and e , the former giving an increased tread to the foot, while

the latter stiffens the inner edge of the sole-plate and supports the hoof at this point.

Having thus described my invention, what I claim as new, and desire to secure by Letters Patent, is—

1. Constructing a shoe with the continuous calk *d*, in combination with the continuous stiffening-rib *e* and the wide bottom surface or groove, *a'*, substantially as herein described.

2. In combination with the improvement embraced in the first claim above, the peculiar manner of curving the shoe at the heel, as shown and described, for the purpose set forth.

ISAAC PEACOCK.

Witnesses.
